VICTOR G. BRASH, OF TAMPA, FLORIDA

PILING FOR SUBAQUEOUS CONSTRUCTIONS

Application filed February 14, 1928. Serial No. 254,284.

5 My invention relates to pilings for subaqueous and other constructions and an object thereof is to provide a metallic piling or unit which may be readily assembled with other identical units to produce a rigid wall or barrier.

The invention further provides an improved joint or connection whereby two adjacent pilings may be quickly but rigidly connected together.

15 My invention also contemplates a hollow piling which when in operative position will interlock with a second piling arranged contiguous therewith or at right angles thereto.

Further the invention provides a sheet metal piling which possesses a maximum strength and at the same time necessitates but a minimum amount of material in its manufacture.

20 With the preceding and other objects and advantages in mind, the invention consists in the novel combination of elements, constructions and arrangement of parts to be herein-after specifically referred to, claimed and illustrated in the accompanying drawings, wherein:

Figure 1 is a fragmentary perspective of a plurality of pilings constructed in accordance with my invention and in operative position to provide a sea wall or barrier;

25 Figure 2 is a fragmentary horizontal sectional view of two adjacent pilings and illustrating the interlocking joint or connection between the same;

Figure 3 is a diagrammatic view illustrating one form of subaqueous construction;

Figure 4 is a similar view illustrating a slightly modified construction;

30 Figures 5, 6, 7 and 8 are diagrammatic views illustrating various types of subaqueous constructions which may be built from my improved piling.

Figure 9 is a fragmentary plan view illustrating a dock wall as constructed with my invention;

Figure 10 is a fragmentary front elevation of the same;

Figure 11 is a vertical section taken on line 11-11 of Figure 9; and

35 Figure 12 is a transverse sectional view of

the bearing piling used in conjunction with the dock wall construction.

Referring to the invention in detail a U-shaped sheet metal piling or unit 5, constructed from relatively stout metal, is provided.

When opposite sides of its crest the U-shaped piling is formed with longitudinally extending grooves or depressions 6. Formed with the crest of the U-shaped member in 60 transverse alinement with the grooves or depressions 6 are oppositely extending U-shaped hook elements 7 whose free edges project slightly beyond the crest and are spaced from the adjacent walls of the grooves or 65 depressions.

At their free ends the parallel legs of the U-shaped piling are bent upon themselves to afford oppositely extending hook elements 8, whose free ends lie between such parallel 70 legs and are adapted to interlock with the hook elements 7 of a second piling arranged in longitudinal alinement therewith.

The hook elements 7 are of such width as to permit the parallel legs of one piling to lie 75 flush with the parallel legs of a second piling so that continuous smooth front and rear walls are provided when a plurality of these pilings or units are arranged in operative position, as illustrated in the drawing. In 80 assembling pilings constructed in accordance with my invention to build a subaqueous structure, the hook elements 7 of one piling are arranged in longitudinal alinement with the hook elements 8 of the adjacent end of a 85 second piling, so that upon driving the latter into the subaqueous base the hook elements of each piling will interlock and detachably connect the two pilings together.

It will be observed that the transverse center line of the hook elements 7 and 8, when interlocked, lie along and are coincident with the transverse center of the crest. This construction materially increases the strength of the pilings at their points of connection with 95 each other.

To meet practical needs the invention may be modified to build various shaped walls as illustrated in Figures 3 to 8, inclusive. The structures disclosed in Figures 3 and 4 are 100

adapted to corners and angle sections, while the structures disclosed in Figures 7 and 8 are junction units. With the construction disclosed in Figures 3 and 4, an L-shaped in cross-section double wall piling 10 is employed. In connection with the construction disclosed in Figure 4 it will be observed that the L-shaped in cross-section piling comprises a pair of spaced angle irons 11 terminating in hook elements 12 which have interlocking engagement with the hook elements 7 of pilings 5, arranged contiguous to each leg of the L-shaped in cross-section piling.

With reference to the construction disclosed in Figures 5 and 6, it will be observed that the piling 10 of Figure 5 is braced by a truss 13 arranged obliquely with respect to the right angular legs of the piling. The piling 10 of the construction disclosed in Figure 6 is substantially like the L-shaped piling disclosed in Figures 3 to 5, inclusive. However, in this instance the legs of the piling 10 are disposed in divergent relation so that two divergent walls may be built therefrom.

25 In connection with the modification disclosed in Figures 7 and 8, a U-shaped column 15 fashioned with hook elements 8 extends at right angles from a piling or unit 5' and is attached thereto by angle plates 16. As disclosed in Figure 8 a pair of plates 17 terminating in hook elements 8 at their outer ends, may be attached to the opposite face of this piling 5' in transverse alignment with the column 15. It will be seen that walls 35 composing my pilings or units 5' may be built at right angles to a main wall from either or both sides of the piling 5'.

Due to the fact that the pilings are connected together at their opposite sides, danger 40 of spreading and eccentric loading is obviated. When a wall constructed from my improved piling is subjected to unusually great earth or water pressures, the pilings may be filled with concrete. When used in this manner each piling will act as a solid beam while the entire wall will act as a monolithic structure.

As a practical illustration of my invention a dock wall constructed therefrom is disclosed in Figures 9 to 12 inclusive. The dock wall indicated at 19 consists of a plurality of the pilings connected together and filled with concrete 20. A plurality of rows of bearing pilings 21 also containing concrete 55 are sunk rearwardly of the wall 19. The wall 19 is tied to concrete anchoring blocks 22 embedded in the ground in advance of the bearing pilings 21 by means of tie rods 23 passing through the anchoring blocks and the 60 wall 19.

The bearing pilings are identical to the pilings or units 5 above referred to. However, to close the open side of the bearing pilings, longitudinal plates 24 are provided 65 having oppositely extending U-shaped hook

elements 25 which have interlocking engagement with the hook elements 8.

What is claimed is:—

In combination, a U-shaped sheet metal piling, horizontal U-shaped hook members formed with the crest of the piling, and extending the entire length thereof, the hook members having their outer legs offset inwardly from the parallel walls of the piling with their terminals spaced from such parallel walls, and reversely extending horizontal U-shaped hook members extending the entire length of the free ends of the parallel walls with their terminals between such walls and adapted for interlocking engagement with mating hook members of an adjacent piling.

Signed at Tampa in the county of Hillsborough and State of Florida this 8th day of February, A. D. 1928.

VICTOR G. BRASH.
